[57] **CLAIM**

The ornamental design for a dual compartmented container for food or the like, substantially as shown and described.

DESCRIPTION

FIG. 1 is a perspective view of a dual compartmented container for food or the like showing my design; FIG. 2 is a plan view of the upper portion in a completely unfolded condition;

FIG. 3 is a plan view of the lower portion in a completely unfolded condition;

FIG. 4 is a view of upper portion in a partially folded condition;

FIG. 5 is a bottom plan view of the upper portion; and FIG. 6 is a exploded perspective view of the complete container.

FIG.6

FIG.1
